Primary Examiner — George D Kirschbaum

(72) Inventor: **Matthew Merzig**, Ashburn, VA (US)

CLAIM

(73) Assignee: **Matthew Merzig**, Ashburn, VA (US)

The ornamental design for an aerodynamic tire valve cap, toy, and/or replica, as shown and described.

(**) Term: **14 Years**

DESCRIPTION

(21) Appl. No.: **29/467,631**

FIG. 1 is a perspective view of an aerodynamic tire valve cap, toy and/or replica (the passenger side valve cap being a mirror image and is not shown) according to my novel design.

(22) Filed: **Sep. 20, 2013**

FIG. 2 is a top plan view thereof;

(51) LOC (10) Cl. **12-15**

FIG. 3 is a bottom plan view thereof;

(52) U.S. Cl.

FIG. 4 is a front elevation view thereof;

USPC **D12/607**

FIG. 5 is a rear elevation view thereof;

(58) **Field of Classification Search**

FIG. 6 is an elevation view from the right side thereof; and

USPC D12/607; D14/5, 223, 206
See application file for complete search history.

FIG. 7 is an elevation view from the left side thereof.
